(57) **CLAIM**

The ornamental design for a hose connector and water stop, as shown and described.

DESCRIPTION

FIG. 1 is a perspective view of a hose connector and water stop in accordance with the present invention;

FIG. 2 is a front view of the hose connector and water stop of FIG. 1;

FIG. 3 is a rear view of the hose connector and water stop of FIG. 1;

FIG. 4 is a right side view of the hose connector and water stop of FIG. 1;

FIG. 5 is a left side view of the hose connector and water stop of FIG. 1;

FIG. 6 is a top view of the hose connector and water stop of FIG. 1; and,

FIG. 7 is a bottom view of the hose connector and water stop of FIG. 1.

The broken lines of FIGS. 1–7 are illustrative of the visible environmental structure of the hose connector and water stop and form no part of the claimed design.

1 Claim, 7 Drawing Sheets
